UNITED STATES PATENT OFFICE

158,619

VEGETABLE CUTTER

Laurine R. Shadduck, Chicago, Ill.

Application June 5, 1948, Serial No. 146,781

Term of patent 14 years

(Cl. D44—29)

To all whom it may concern:

Be it known that I, Laurine R. Shadduck, a citizen of the United States, and a resident of Chicago, in the county of Cook and State of Illinois, have invented a new, original, and ornamental Design for a Vegetable Cutter of which the following is a specification, reference being had to the accompanying drawing, forming a part thereof.

Fig. 1 is a side elevational view of a vegetable cutter embodying my invention;

Fig. 2 is a plan view of the subject matter disclosed in Fig. 1; and

Fig. 3 is an end elevational view thereof.

I claim:

The ornamental design for a vegetable cutter, as shown and described.

LAURINE R. SHADDUCK.
